US00D464566S

(12) **United States Design Patent** (10) Patent No.: **US D464,566 S**
 Anchor et al. (45) Date of Patent: ** Oct. 22, 2002

(54) **PACKAGING CONTAINER**

(75) Inventors: **David Anchor**, Itasca, IL (US); **Tommy Bo Goran Ljungstrom**, Hoor (SE); **Mauro Morandi**, Modena (IT)

(73) Assignee: **Tetra Laval Holdings & Finance S.A.**, Pully (CH)

(**) Term: **14 Years**

(21) Appl. No.: **29/061,695**

(22) Filed: **Oct. 29, 1996**

(30) **Foreign Application Priority Data**

Jul. 10, 1996 (IT) MI9600405

(51) LOC (7) Cl. **09-07**

(52) U.S. Cl. **D9/432**

(58) Field of Search D9/414-418, 419, D9/431, 432; 229/109, 116.1, 137, 138, 920
